CORROSION RECORDER

Marselio G. Fontana, Wilmington, Del., Gordon W. Kidder, Bridgeport, Conn., and Philip B. Kraus, Roselle Park, N. J., assignors to E. I. du Pont de Nemours & Company, Wilmington, Del., a corporation of Delaware

Application January 28, 1941, Serial No. 376,288

1 Claim. (Cl. 175—183)

This invention relates to apparatus for recording the corrosive nature of various media, and more particularly to devices for automatically determining and controlling the corrosiveness (incipient or advanced) of solutions or slurries which come in contact with metallic equipment, elements or parts employed in various commercial operations. By the term "incipient corrosion," we intend to include that degree of corrosion which takes place prior to any appreciable deterioration or actual corrosion of an involved metal or element.

When electrodes composed of dissimilar metals are suitably immersed or otherwise disposed in separated relationship in a contacting corrosive solution, a difference of electrical potential is set up therebetween. When the corrosive condition of the solution towards a particular metal or alloy increases, a rise in the difference of potential between the electrodes often results. Conversely, when the corrosiveness decreases or weakens, a reduction in the electrical potential often takes place.

For instance, if two electrodes composed of dissimilar metals are immersed in an acidic or like corrosive solution and a circuit is formed by connecting them together by means of an electrical conductor, such as copper wire, a current will flow through the conductor from one electrode to the other. Since the flow of current through a conductor of fixed resistance is proportional to the voltage applied at its terminals, the interpositioning in the circuit of a sensitive instrument, such as a potentiometer, will directly indicate the electrical potential which exists between said electrodes. Since the difference of electrical potential between two electrodes is often a function of the corrosiveness of the solution and a definite relationship appears to exist between the current and the rate at which the electrodes corrode or deteriorate, the corrosive nature of any solution may be readily ascertained by measuring this difference in electrical potential between electrodes.

The resistance which a contacting metal or alloy, such as stainless steel, exhibits towards corrosive media largely depends on the ability of such media to form an adherent surface or protective film on the metal or alloy. If this film should be completely removed by either chemical or mechanical action, the metal or alloy becomes highly sensitive to the corrosive action of the media and will thereupon become highly susceptible to rapid deterioration. If this protective film is not permitted to reform within a relatively short period of time, the metal or alloy will continue to

corrode or dissolve. The continued presence of the abnormally corrosive solution will therefore hinder or entirely prevent the reformation of the protective film.

5 The continued, uninterrupted presence of a protective film on the metal may also prove disadvantageous because of its tendency to act as an insulator to prevent the immediate detection and correction of an undesired change in the corrosive characteristics of a liquid, either to the incipient or advanced stage. Thus, if the media the corrosive nature of which is being ascertained is not originally corrosive towards a particular metal, a protective film will build up on the electrodes and a subsequent change in the corrosive nature of the solution will not be detected until the protective film is completely removed from the electrodes and the latter then replaced in the solution. In the interim, if an abnormal corrosion condition actually exists, irreparable damage may ensue.

It is accordingly among the objects of this invention to provide novel means for overcoming the above as well as other difficulties which have been heretofore encountered in corrosion recording devices. A further and particular object is to provide useful means for immediately, accurately and practically ascertaining when a non-corrosive solution changes to one which is corrosive in character. A still further object is to provide novel means for ascertaining the film forming ability or capacity of a solution on metal or alloy electrodes. An additional object is to provide means for actuating a corrective control mechanism or signalling device when a given solution fails to replace a protective film on a metal electrode. An additional object is to provide a novel combination of elements adapted to automatically control the qualitative nature of a given solution, as well as automatically correct and remedy incipient or advanced corrosiveness upon its occurrence. Other objects of the invention will be apparent from the ensuing description and accompanying diagrammatic drawing.

The above mentioned as well as other objects and advantages are attainable in our invention which comprises electrically indicating and/or controlling or regulating the corrosive or non-corrosive characteristics of a solution by providing, in combination, connected electrodes or terminals in contact with said solution, electrically sensitive means responsive to a difference in electrical potential in the circuit, arranged in series with said electrodes and solution, and additional

means for periodically removing any protective film formed on said electrodes.

In a more specific and preferred embodiment of our invention, a novel apparatus for indicating the film-forming ability of solutions or slurries on metals or alloys is provided, which comprises, in combination, an electrical circuit, including a pair of electrodes of dissimilar metals or alloys connected together by an electrical conductor, said electrodes being in contact with or immersed in a solution or slurry to be tested, a recorder potentiometer interpositioned in said circuit responsive to the current flowing therein, a battery or other source of electrical current in said circuit adapted to periodically impress a counter E. M. F. in said circuit and remove any protective surface film formed on said electrodes, and a signalling and/or corrective control means actuated by said potentiometer for indicating and/or correcting the failure of the solution or slurry to reform said protective film on said electrodes after each periodic removal.

The invention will be more readily understood when considered in connection with the ensuing description and accompanying drawing, the latter diagrammatically illustrating one preferred adaptation thereof and wherein a solution or slurry to be tested is continuously supplied to and withdrawn from a suitable vessel or container. For purposes of illustration, the invention will be described as applied, for instance, to the protection of a delicate, stainless steel type of screening apparatus (not shown) and such as is employed in centrifugal or other types of apparatus. Such screening element may be provided, for instance, with a plurality of small openings or apertures of, say, about .01" in diameter and during use is in continuous contact with a solution such as hydrogen sulfide which is not normally corrosive to the particular alloy of which said screen element is made up. Under certain conditions of operation, however, especially when the sulfide content of such solution increases due to a desired or unavoidable change in the operating procedure, the solution may become more or less corrosive to said screen and thereupon deleteriously attack and damage the metal. Unless this corrosive condition is remedied within a relatively short period of time, such as by substantially immediate neutralization after reaching a corrosive state, the openings in the screen element will become unduly enlarged and seriously damaged, due to corrosion attack, to ultimately render the screen wholly unfit and entirely ineffective for its intended use and purpose.

Referring now to the accompanying drawing (which is obviously not to scale) a vessel or container 10 is shown, provided with a suitable inlet 11 and outlet 12, and adapted to retain a suitable solution 13 which may be either corrosive or non-corrosive in nature, e. g., acid, alkaline, or neutral. If desired, the container 10 may conveniently comprise an enlarged conduit or section of pipe in the main flow, or, alternatively, may comprise auxiliary equipment associated in a bypass line which may be in either valved or open communication with said main flow. Suitably positioned for contact in the solution 13 and in substantially spaced relationship from each other, but out of contact with the container 10, two electrodes 14 and 15 are provided, constructed, preferably, of dissimilar metals or alloys. One such electrode consists preferably of substantially the same type of metal or alloy

as the equipment which is being protected, while the other electrode consists substantially of a metal or alloy which is more resistant to corrosion than the one to be protected. For instance, 5 if the screen element or other operating parts which are to be protected should be constructed of an alloy composed of, say, 18% chromium, 8% nickel, .07% carbon, and the remainder substantially all iron, one of the aforesaid electrodes is 10 preferably constructed of this same composition. The other electrode may conveniently be constructed of a stainless steel type of composition known to possess positive resistance to the solution under test, if and when the same should be 15 come corrosive in character and to any given degree. For example, in the instance under illustration, said other electrode may conveniently be constructed of a stainless steel known in the trade as "Carpenter No. 3" containing about 20% 20 chromium, 1% copper, .25% carbon, and the balance substantially all iron.

The electrodes 14 and 15 may be suitably supported in the solution 13 in any desired manner and by any desired and convenient means. Suitably disposed on said electrodes are rubber covering elements 16, adapted to protect them at the liquid-air line, this being essential to prevent excessive rates of corrosion of the metal, and also inaccurate potential readings. Suitably connected to said electrodes, electrical conducting wires 17 and 18 are provided, which lead and are connected to a recording potentiometer or equivalent voltage measuring device 20, of any well known operable electrical make through a relay 30 21, whereby the potential difference between the electrodes will be recorded on said potentiometer. The solution to be tested completes the electrical circuit.

In order to maintain the electrodes at maximum sensitivity at all times, periodically we remove any protective film formed on said electrodes, thereby permitting one to determine whether the protective film can or cannot be removed by the solution in question. In the present embodiment of the invention, this may be accomplished by providing in the circuit a suitable source of electric current 22, such as a storage battery, dry cell battery, transformer, etc., the leads of which are connected to the electrodes 40 14 and 15 by means of the electrical conductors 23 and 24 through a 2-pole relay 21. During the interval of time the electric current from the battery 22 is being impressed in a reversed direction from the electrodes, a solenoid 25, actuated by a time element or clock 26, is energized, causing the battery circuit to close and the potentiometer circuit to open. The current flowing from the battery passes through the electrodes in a reverse direction to the normal flow and removes 45 any protective film that has been formed on said electrodes. After a designated time interval, the solenoid 25 becomes de-energized, the relay 21 takes up its normal position, cutting out the battery 22 from the circuit, and cutting in the recording potentiometer 20. Since the electrodes now have no protective film thereon, a high potential difference will be recorded on the potentiometer. If the solution is not corrosive to the alloy, a coating will form on the electrodes and the potential difference between the electrodes will consequently decrease until the solenoid is again energized, impressing a counter electromotive force through the electrodes.

Should the solution 13 become corrosive at any time towards the electrodes, it will fail to replace

the protective film and consequently the potential difference, as recorded on the potentiometer, will increase or remain at a relatively high value, rather than decrease. If, after a predetermined time interval, the potential difference between said electrodes is not below a predetermined value, a relay 27 becomes energized to actuate a suitable indicating or signal element 28, such as an alarm or flashing light. Operation of said alarm will direct an operator's attention to the fact that the solution being tested is not of desired film-forming character and manual steps can then be taken to neutralize or otherwise correct the character of said solution and render it substantially non-corrosive. Alternatively, the indicating element 28 may comprise means for automatically controlling, correcting and/or regulating the character of the solution 13 when it becomes substantially corrosive in nature. Thus, element 28 may take the form of a suitable relay switch (not shown) an arm of which functions, upon actuation after being cut in the circuit to open a suitable valve-controlled conduit leading from a suitable source of supply, such as a tank or vessel (also not shown), wherein a neutralizing or other compensating or corrective agent or fluid is retained, whereby a requisite and sufficient quantity of such agent or fluid will be introduced into the container 16 to reduce or neutralize the corrosive character of the solution present therein. By such type of automatic means, the liquor or slurry present in the container can be maintained relatively constant qualitatively and in accordance with the adjustment of the automatic controlling relay switch.

For periodically impressing a counter E. M. F. through the electrodes, a suitable timing element, such as a clock 26, connected to a relay (not shown) may be provided. Said time clock may comprise any well-known type of operable electrical make which is adapted to actuate a relay for a predetermined interval of time. In our preferred embodiment, the counter E. M. F. from the battery is impressed across the electrodes for a period of about 30 seconds after the time clock cuts the battery from the circuit. It has been found that, for the particular corrosive materials being tested, a counter E. M. F. of 30 seconds through the electrodes will effect desired removal of the film formed thereon. Obviously, for any given corrosive material, it will be necessary to determine the time required to completely remove the protective film from the electrode, but such procedure will be merely a routine matter and readily understood by those skilled in the art.

While the invention has been described in connection with certain preferred embodiments thereof, it is to be understood that the same is not to be considered as limited thereto. For instance, it will be readily apparent that while particular types of electrodes have been employed herein, other types of dissimilar metallic electrodes may be used. In any given embodiment of the invention it is only essential that at least one of the plurality of electrodes employed shall be of such nature that it is capable of forming a protective film against non-corrosive media, and that it be of the same material as the equipment which is being protected. Conveniently, the other or remaining electrodes may consist of any other dissimilar metal or alloy. For example, electrodes having the following compositions have also been successfully employed: 18% chromium, 8% nickel, 2½% molybdenum, 0.08%

carbon, and the balance substantially all iron and 50% cobalt, 15% tungsten and 30% chromium. Other useful types or combinations of dissimilar metals or alloys will be obvious to those skilled in the art.

Further, the means disclosed for periodically removing the surface film from the electrodes are not to be construed as in limitation of our invention. While in practice it has been found more convenient, preferable and efficient to employ electrical means for impressing a counter E. M. F. to the electrodes, as above described, other means may be employed, if desired. For example, the surface film may be periodically removed by mechanical means adapted to scrape the film from the electrodes or by placing in the solution in which said electrodes are immersed a chemical which will be corrosive to the alloy or metal used for the electrodes. In such operations, however, it will be necessary and desirable to have the electrodes situated on a by-pass to the main flow in order that the corrosive media will not come in contact with the equipment to be protected. Another means for periodically removing protective film from the electrodes involves increasing the temperature of the solution being tested so that it will dissolve the surface film. While these methods all have certain advantages, it is nevertheless preferred to employ electrical means for automatically and periodically removing the surface film from the electrode as soon as such removal can be quickly and practically accomplished and while the process and all operating parts in conjunction therewith are maintained in status quo and under substantially the same prevailing conditions of operation. Although, as indicated, the device is preferably automatically controlled, this is not an essential limitation to the operation of our invention since the film can be removed by manual control of the electrical energy. Since the automatic alarm, signalling or solution-corrective equipment requires less operating attention and gives a positive indication at all times of the condition of the solution being tested, such automatic method constitutes our preferred form of the invention.

As will be evident, our invention has wide application in measuring the film-forming ability of many varied types of solutions, liquids or slurries, whether acid, alkaline or neutral, on alloys and metals. Thus, it will be found especially suitable for use in conjunction with the testing, control or regulation of relatively dilute or concentrated sulfuric, hydrochloric, nitric, phosphoric, etc. or other mineral or organic acid-containing solutions; of metallic salt solutions, including metallic sulfates, halides (chlorides, bromides, fluorides) etc., especially those of iron, zinc, aluminum, etc.; and of caustic solutions, such as those of potassium, sodium or barium hydroxide; as well as mixtures thereof.

As will be evident, novel means is provided by our invention for continuously and positively determining and/or controlling the state or condition of any type of liquid media, and for particularly ascertaining whether such media is corrosive or non-corrosive in nature. Further, it provides means for automatically controlling and regulating the quality or characteristic of a given liquid or aqueous slurry to any desired condition or state. By its use, continuous information is had of the characteristics of the solution under test, whereby one may immediately ascertain at all times whether the solution in question will or

will not attack or corrode metallic parts and equipment employed in commercial plant operations. From this standpoint alone, it has a high degree of practical value, especially as applied to processing costs and continuous operations. Another outstanding advantage resides in the fact that periodic removal of the protective film from the electrodes permits one to ascertain whether the protective film can or cannot be reformed by the solution under test. This renders the device very much more sensitive as a corrosion recorder in that it permits determination as to the existence or non-existence of incipient, as distinguished from advanced, corrosiveness. When the electrodes are employed without means for periodically removing such film, no measure of the film-forming ability of the liquid can be obtained. The particular liquid being tested does not need to destroy the protective film, but needs simply be incapable of reforming such film. Since any injury to the protective film, either through corrosive media or by mechanical means, such as the rupture of the film by abrasion or otherwise, will cause abnormal corrosion to take place, it is important that the film-forming ability of the liquid be measured and known at all times, especially if a continuous type of operation is to be assured. Obviously, this aspect of the invention is of the utmost practical importance. Since the resistance of stainless steels employed in plant equipment towards liquors which are corrosive or may become corrosive in character depends upon the formation of an adherent surface film on the steels, it is very important that immediate detection be had as to whether the surface film can be removed by the action of the liquor itself and thus become subject to rapid corrosion and deterioration. In accordance with our invention, we advantageously ascertain the presence of corrosive conditions through periodic sensitizing of the elec-

trodes and before any appreciable attack occurs on the involved metals or parts. Thus, one may readily determine whether or not abnormal corrosion would occur if the protective surface film on the metals and alloys involved should be removed by any means, whether mechanical, electrical, or chemical. Thus, by the immediate ascertainment of incipient corrosiveness, the existence of subsequent abnormal corrosion can be readily forecast.

10 We claim as our invention:

Apparatus for indicating the film-forming ability of solutions and slurries on metallic materials, comprising in combination, an electrical circuit, a source of electrical energy therefor, a pair of spacedly-disposed, interconnected electrodes in said circuit, composed of dissimilar metals and immersed in a solution to be tested, one of said electrodes conforming substantially to the composition of the metal material towards which the 15 action of said solution or slurry is to be determined, a voltage measuring device also disposed in said circuit and responsive to the current flowing therein, a second electrical circuit, a source of electrical energy therefor, means included in said 20 25 30 35 second circuit for closing said first circuit and periodically impressing from the source of energy in said second circuit a counter E. M. F. in said first circuit to remove, at controlled time intervals, any protective film formed on said electrodes and periodically expose them, while in film-free condition, to the action of the solution being tested, and indicating means actuated by said voltage measuring device for indicating the failure of the solution or slurry to reform a protective film on said electrodes after said periodic counter E. M. F. has been impressed in said first circuit.
